UNITED STATES PATENT OFFICE.

JOHN F. O'CONNOR, OF CHICAGO, ILLINOIS, ASSIGNOR TO WILLIAM H. MINER, OF CHICAGO, ILLINOIS.

BUMPING-POST.

1,122,991.

Specification of Letters Patent. Patented Dec. 29, 1914.

Application filed November 24, 1913. Serial No. 802,847.

To all whom it may concern:

Be it known that I, JOHN F. O'CONNOR, a citizen of the United States, residing at Chicago, in the county of Cook and State 5 of Illinois, have invented a certain new and useful Improvement in Bumping-Posts, of which the following is a full, clear, concise, and exact description, reference being had to the accompanying drawings, forming a 10 part of this specification.

This invention relates to improvements in bumping posts.

Objects of the invention are to provide a bumping post of large capacity so constructed that it is extremely rigid and arranged to overcome any tendency of the shock absorbing device to be deflected from its proper position either sidewise, up or down, when it is bumped by a railway car 20 or locomotive; to provide a bumping post in which the shock absorbing device is readily removable and interchangeable to facilitate repairs; and to provide a bumping post in which the shock absorbing device is mounted and freely movable within a hollow casing formed in a casting having bracing flanges extending laterally, downwardly, and rearwardly therefrom.

The invention furthermore consists in the 30 improvements in the parts and devices and in the novel combinations of the parts and devices as herein shown, described or claimed.

In the drawing forming a part of this 35 specification, Figure 1 is a part side elevation, part section of the shock absorbing device employed in my improved bumping post. Fig. 2 is a transverse, sectional view, the left half of which is taken on the line 40 2—2 of Fig. 1 and the other half of which is taken on the line 2—2 of Fig. 1. Fig. 3 is a longitudinal, vertical, sectional view showing the improved bumping post and the manner of anchoring the same to a concrete 45 foundation and its relation relatively to the track rails and Fig. 4 is an end view, parts being in section, as the bumping post is viewed from the line 4—4 of Fig. 3.

In said drawing, the foundation to which 50 the bumping post proper is anchored is shown as comprised of a bed of concrete 10 having a plurality of longitudinally extending I-beams 11 embedded therein, to the tops of which are secured a plurality of 55 transversely extending I-beams 12, the lat-

ter being above the top of the concrete. To strengthen and reinforce the concrete bed and hold the I-beams 11 in proper place, a plurality of transversely extending channels 13 are provided on the top of the concrete which are held in place by vertically extending bolts 14 which pass down through the concrete and through plates 15. Secured to the ends of the transversely extending I-beams 12 by suitable angle 60 plates 16 are two vertically extending heavy plates 17, the forward edges of which are beveled, as shown at 18 in Fig. 3. To the tops of the I-beams 12 is secured a horizontal floor plate 19 and on the latter are mounted the track rails 20, see Fig. 4.

Secured to the plates 17 is a heavy casting A which, as shown, comprises a cylindrical casing 21 open at its front end, a horizontally and rearwardly extending 75 thrust-resisting flange 22, laterally extending and upwardly inclined side flanges 23 on each side of the casing, a pair of downwardly extending, spaced, arcuate flanges 24, parallel securing side flanges 25 and 80 vertical, diagonally disposed flanges 26. As will be understood, all the flanges of the casting which extend to the plates 17 are securely riveted thereto.

The casing 21 has mounted therein a shock 85 absorbing device designated generally by the reference B which is shown most clearly in Fig. 1. As shown in the drawing, the shock absorbing device B comprises a spring case 27 having a flange 28 at each end thereof 90 and to each of which is secured by suitable bolts and nuts, a flanged friction shell 29 having an inner cylindrical friction surface 30. The spring case 27 is cylindrical in general outline but is shaped to conform to 95 and to provide pockets for a plurality of circularly arranged sets of springs 31, each set comprising an outer heavy spring and a lighter spring nested therewithin, as shown most clearly in Fig. 2. A central set of 100 springs is provided within the circularly arranged sets so that, as shown, there are seven sets of springs adapted to take up the shock in the manner hereinafter described.

In each friction shell 29 there is mounted 105 a set of three friction shoes 32 each having an outer arcuate friction face coöperable with the friction face 30 of the shell. Each friction shoe 32, on its inner side, is provided with a wedging face 33 coöperable 110

2
with a correspondingly inclined wedge face 34 formed on a wedge 35, the latter having three wedge faces 34 coöperating respectively with the three wedge faces 33 of the friction shoes. Between each pair of wedge faces 33 and 34 there is mounted an anti-friction roll 36 to facilitate the release of the mechanism after it has been operated. On their inner faces, the friction shoes are each provided with a flange 37 against which seats one end of a preliminary compression spring 38, the other end of which seats against a spring cap 39 having a cylindrical portion 40 loosely slidable within the friction shell and guided thereby. The two spring caps 39 are pressed away from each other by the sets of springs 31 within the spring case and their outward movement is limited by circumferentially extending flanges 41, formed integrally therewith, which engage shoulders 42 formed on the inner ends of the friction shells 29, see Fig. 1. To hold the wedge, friction shoes and preliminary compression spring of each shock absorbing device in assembled position, there is provided a bolt 43 extending from each spring cap to its corresponding wedge. Each friction shell 29 is surrounded by a heavy ring 44 to prevent bursting of the shell under the enormous radial pressure exerted thereon under buffing action. Each edge 35 is provided at its outer end with an integral follower-acting plate 45. The shock absorbing device B is placed within the casing 21, and as will be understood, is bodily slideable therein and so proportioned that one of the wedge members will engage the rear inner wall 46 of the casing 21 and the other wedge will extend out of the casing 21 and is arranged at such a height that the draw-bar or buffer of a car will engage therewith. At the outer end of the casing 21 and on the interior thereof, is detachably secured by bolts or otherwise, a retaining ring 47 to hold the shock absorbing device within the casing.

In operation, the shock resulting from a car or locomotive striking the bumping post will be partly taken up by the preliminary compression of the springs 38 and the friction created between the friction shoes and friction shells and the final and heavier portions of the shock will be transmitted to the central sets of heavy springs 31 through the spring caps 39 which will be engaged by the friction shoes 32 after the springs 38 have been fully compressed. On account of the fact that the shock absorbing device is loosely mounted within the casing 21, it is double acting, whereby its capacity is also doubled, so that the capacity of the bumping post, in actual practice will be more than one million pounds.

From the preceding description, it will be seen that the casting A is so constructed

that it provides an extremely rigid support for the shock absorbing device and prevents the latter from being deflected out of proper position, which has been a tendency of bumping posts used hitherto. The foundation and anchoring members for the casting of the bumping post are also of very solid and substantial construction, thereby adapting the post to absorb extremely heavy shocks. The detachable ring 47 renders it easy to take out and repair or replace the shock absorbing device at any time.

Although I have herein shown and described what I now consider the preferred embodiment of my improvement, yet it will be understood that various changes and modifications may be made without departing from the spirit of the invention, and all such changes and modifications are contemplated as come within the scope of the claims appended hereto.

I claim:—

1. A bumping post including, in combination: stationary anchored members having a casting rigidly secured thereto, said casting having a hollow casing open at one end formed therein; and shock absorbing mechanism mounted in and held in proper operative position by said casing, substantially as specified.

2. A bumping post including, in combination: stationary anchored members having a casting rigidly secured thereto, said casting having a hollow casing and flanges extending laterally and rearwardly therefrom and secured to the stationary members to thereby brace the casing against lateral and thrust shocks; and shock absorbing mechanism mounted within said casing, substantially as specified.

3. In a bumping post, a shock absorbing device comprising a spring case, a friction shell at each end of said case, friction shoes and a wedge within each friction shell, springs within the spring case, and a movable spring cap at each end of said springs adapted to be engaged by the friction shoes to compress said springs, substantially as specified.

4. In a bumping post, a shock absorbing device comprising a spring case, a friction shell at each end thereof, friction members within each shell, main springs within the spring case, a movable spring cap at each end of said springs, and preliminary compression springs between each spring cap and the adjacent friction members and normally separating the same, some of the friction members in each shell being adapted to engage the spring caps during the first part of the operation of the device and to then press said spring caps to compress the main springs, substantially as specified.

5. In a bumping post, a double acting shock absorbing device having a friction

shell, friction shoes, a wedge and preliminary compression spring at each end thereof and main springs interposed between the friction shock absorbing means, substantially as specified.

6. A bumping post including, in combination: a casting mounted on stationary anchored plates, said casting having an integral, hollow casing; and a shock absorbing device bodily slidably mounted within said casing, substantially as specified.

7. A bumping post including, in combination: a casting mounted on stationary anchored plates, said casting having an integral, hollow casing; and a shock absorbing device bodily slidably mounted within said casing, said shock absorbing device being double acting, substantially as specified.

8. A bumping post including, in combination: a casting secured to stationary anchored members, said casting having an integral hollow casing, and downwardly, laterally and rearwardly extending flanges; and a shock absorbing device bodily slidably mounted within said casing, said de-

vice having a spring case, springs mounted therewithin, a friction shell at each end of said spring case, and coöperating friction shoes and wedge within each shell, the innermost wedge engaging the rear end of the 30 casing within which the shock absorbing device is mounted and the other wedge extending outwardly therefrom, substantially as specified.

9. A bumping post including, in combination: a shock absorbing device; supporting members in which said device is mounted; and means for anchoring said supporting members said means including a bed of concrete having longitudinally extending 40 beams embedded therein, transversely extending beams secured to the first named beams, plates on the top and bottom of said concrete and connecting bolts therefor, substantially as specified.

JOHN F. O'CONNOR.
